Application December 16, 1943, Serial No. 514,448

16 Claims. (Cl. 101—423)

1

The present invention relates to a method for continuous printing of textiles and the like and apparatus to effect such method, and the present application is a continuation-in-part of our application Serial No. 487,058, filed May 14, 1943.

A general object of the invention is the provision of an efficient continuous method of printing textiles and the like which is readily practiced, unusually speedy, minimizes wastage of printed material, makes possible the elimination of a back grey, and effects a very great saving in costs of labor, installation and operation while assuring the production of a superior product with a minimum wear of equipment and requirement of replacement of parts; and apparatus to carry out such method which is extremely simple, very economically constructed, readily and cheaply operated, sure and efficient in function, unusually long lived, requires little if any attention with respect to repair and replacement of parts, is characterized by an endless backing blanket of minimum length undue wear of which is avoided, and which will produce with unusual speed a product of excellent quality.

It has been a general practice in the continuous printing of long strips or work-pieces of textiles and the like with inks or color pastes of various colors arranged in repeated patterns and designs to employ a large press cylinder about which is looped an elongated endless backing blanket, made of rubber or of a laminated water-repellent fabric to constitute a resilient backing for the work-piece having an outer surface substantially impervious to moisture such as washing fluid. In the printing of the work-piece it is fed between that portion of the backing blanket which is looped about the press cylinder and a gravure roll or rolls that transfer printing ink from a fount or founts to the work-piece. As the ink is transferred from the gravure roll or rolls to the work-piece some of it tends to penetrate through the latter to collect on the backing element. Also, since it is desired to have the designs or patterns extend completely to the selvages of the work-piece, the gravure roll or rolls are normally wider than the work-piece and, as a result, ink will be applied directly to zones of the backing element beyond the selvages of the work-piece. Without protection of the backing blanket these ink deposits collect on the outer surface thereof and a so-smeared blanket will tend, on its return to the press cylinder, to smear or blotch succeeding yardages of the work-piece unless effectively cleansed. It is common practice to attempt to avoid such smearing and blotching by feeding be-

2

tween the work-piece and the backing blanket a strip of fabric called a "back grey" which, after use, is washed to remove ink or color pastes and then dried for reuse. The back grey eventually has to be discarded and this entails a large expense which may cause an increase in production costs of the printed product of as much as one-quarter cent a yard. Accordingly, attempts have been made to eliminate the necessity of using a back grey by washing and drying the backing blanket of the printing machine. Such proposals have been featured by complicated structures requiring unusual and undesirably long lengths of costly backing blanket material and by heating means completely to remove the washing fluids from the blanket, such as drying cans or heating chambers through which the blanket is passed back and forth. Such structures have been expensive to install, operate and maintain and have unduly shortened the life of the blanket. Further they have tended to slow up operations so that desirably high speeds of operation of the printing machines have been inadvisable, and if some provisions are not made for cooling the blanket before it reaches the gravure roll or rolls heat will be transferred to the latter to such extent as to tend to congeal inks or color pastes causing further difficulties. Printing machines equipped with such washing and drying means further have made it impractical or impossible to use a back grey therewith for certain productions where such may be desired.

A more specific object of the invention is the provision of such a method characterized by the employment of an endless backing blanket which is led from the press cylinder directly to washing and scrubbing means and substantially directly therefrom back to the press cylinder past moisture and lint- and ink-removing means, whereby a blanket of minimum length is employable while assuring its return to the printing means in a substantially cleansed condition with a retention in the printing area of only a very small amount of moisture due to washing fluid, e.g., an amount which is just sufficient to help hold the work-piece in position and enhance color penetration thereof without tending to make the colors run.

Another object of the invention is to provide in such procedure a mechanical, washing fluid-removing step which efficiently eliminates from the outer surface of the blanket excess fluid without undue wear thereof.

A further object of the invention is the provision of a removal of almost all of the moisture from the printing area of the blanket by doctor

55

blade means which removes such washing fluid by a plowing action to permit it to be discharged by falling while lint and ink particles are carried off to an edge of the blanket for elimination by a sheering action.

Still another object of the invention is the provision of apparatus to effect such procedure which is simple and economically constructed characterized by washing and scrubbing means which limits cleaning and wetting action to the ink-smeared printing area of the blanket, thereby avoiding creeping of moisture to the back of the blanket and eliminating difficulties that would be attendant thereon.

Still further object of the invention is to provide such apparatus which removes almost all of the washing fluid without undue wear, by doctor blade means, of the important area of the blanket, i. e., the printing area, due to automatic lubrication thereof by the washing fluid.

An additional object of the invention is to provide such a method and such apparatus for effecting the same which efficiently eliminate or minimize the difficulties attendant upon the accepted practices of the prior art which have come to be thought of by those skilled in the art as being unavoidable necessary evils or eliminable only in part at the expense of other desired characteristics.

Other objects of the invention will in part be obvious and will in part appear hereinafter.

The invention accordingly comprises the several steps and the relation of one or more of such steps with respect to each of the others, and the apparatus embodying features of construction, combination of elements and arrangement of parts which are adapted to effect such steps, all as exemplified in the following detailed disclosure, and the scope of the invention will be indicated in the claims.

For a fuller understanding of the nature and objects of the invention, reference should be had to the following detailed description taken in connection with the accompanying drawings, in which:

Fig. 1 is a schematic side elevational view, with parts broken away and in section, of an embodiment of the present invention;

Fig. 2 is an enlarged elevational section of washing, scrubbing and moisture-removing means taken on line 2—2 of Fig. 1;

Fig. 3 is an enlarged cross-section, with parts broken away, of the apparatus shown in Fig. 2, taken on line 3—3 of Fig. 1;

Fig. 4 is an enlarged fragmentary sectional view of press cylinder, backing blanket and ink-applying means showing a work-piece in printing position, and taken on line 4—4 of Fig. 1;

Fig. 5 is an enlarged fragmentary face or elevational view of the ink-smeared blanket after it has passed the washing and scrubbing means, graphically indicating the dual action of an embodiment of the doctor blade shown therein;

Figs. 6, 7 and 8 are enlarged fragmentary views of portions of the blanket and different embodiments of the doctor blade of the invention which may be employed in the practice of the latter and showing different positions thereof which are possible; and

Fig. 9 is a fragmentary face view on an enlarged scale of the blanket and associated doctor blade graphically showing features of characteristic fluid removing and cleaning operations.

Referring to the drawings, like numerals identify like parts throughout. An endless backing

blanket 10 has a loop 11 thereof passed around a press cylinder 12 to provide a resilient facing for the cylinder to act as a printing backing. A printing or gravure roll 13, of which a plurality 5 may be provided when desired, has an engraved surface rotating against a pick-up roll 14 immersed in ink or color paste fount 15. A roll 16 of textile or the like supplies a workpiece 17 to between the loop 11 of the backing blanket and the gravure roll 13. The backing blanket 10 is carried over an idle supporting roll 18 fixed on a shaft 19 supported in an upright-frame structure 20. Blanket 10 is then carried down beneath an idle roll 21 fixed on a shaft 22 rotatably supported on the frame 20 and carrying a spur gear 23. The blanket 10 is carried from roll 21 substantially directly back to the press cylinder without proceeding through any drying means characterized by an elongated path. Preferably a 15 reach or portion 24 of the blanket 10 moves from idle roll 21 upwardly at an acute angle with a vertical plane to a tensioning roll 25 and then over an idle roll 26 on its return to press cylinder 12.

The frame structure 20 supports washing and scrubbing means which may comprise a brush roll 27 partially immersed in a bath 28 of washing fluid contained in an elongated pan or trough 29 fitted with an overflow pipe 30 to predetermine the level of the washing fluid therein. The brush roll 27 is rotated in a direction opposite to the direction of the blanket as it is carried beneath the roll 21 by means of a spur gear 31 which is meshed with an idle gear 32 in turn meshed with gear 23. It will be understood that one or more, 20 such as two or three, brush rolls 27 may, if desired, be operated from gear 23 and employed to scrub the outer surface of the blanket 10 as it passes around the roll 23.

Although washing fluid may be supplied to the 25 outer surface of the blanket as it passes beneath the roll 23 solely by the brush 27 due to the partial immersion of the latter in the bath 28 thereof, it is preferably chiefly supplied by spraying means. This spraying means may comprise an elongated nozzle 33, such as a piece of pipe closed at one end, provided with a plurality of longitudinally spaced apertures for egress of washing fluid and fitted with a flexible supply hose 34. The spraying nozzle 33 which is adapted to supply washing fluid to the outer surface of the blanket after it has left the scrubbing means is preferably flexibly supported or suspended for free lateral movement such as by chains 35, 35 fastened to brackets 36, 36 fixed to the frame structure 20. The spray nozzle 33 carries at each end an abutting plate or guide projection or rod 37 so as to receive therebetween the edges of the reach 30 of the blanket 10 so that during the rapid travel of the blanket should the latter weave back and forth a limited degree the spray nozzle 33 will be moved laterally simultaneously therewith to assure spraying the outer surface of the blanket in a limited area.

Since backing blanket 10 is received immediately from the press cylinder 12 by the washing and scrubbing means there is an insufficient time interval for the inks thoroughly to dry thereon. However, it has been found to be desirable to arrange a similar spray nozzle 133 suspended by flexible supports or chains 135, 135 from similar brackets 136, 136 fixed to the frame structure 20 ahead of the scrubbing means or brush roll 27. Spray nozzle 133 may also be equipped with separate guide projections but preferably is fixed to

nozzle 33 for lateral movement therewith by rods 31, 37 which constitute the guides for nozzle 33.

Excess washing fluid is removed from the blanket in accordance with the present invention by doctor blade means 38 which may comprise an elongated support 39 carried by rotatable shaft means 40, 40 supported in end bearings 41 and 42 fixed upon the frame structure 20. Upon shaft means 40 is splined a spur gear 43 meshed with a worm 44 rotatably supported, such as by the end bearing structure 42, and fitted with a hand wheel 45 so that by manipulation thereof shaft 40 and blade support 39 may be rotated. An elongated, relatively thin, doctor blade 46, preferably of metal such as steel, or other suitable rigid material which may resist corrosion by the chemicals, is mounted upon the rotatable support 39 and is provided with portion 47 having a relatively sharp edge 48 adapted to press firmly against the outer surface of the reach 24 of the blanket 10, as is more clearly indicated in Fig. 6, with the edge portion 47 lying substantially in a plane which makes an acute angle α , such as about 45° with the surface of the blanket reach 24 on the leading side of the blade edge 48. This will assure plowing action for removal of almost all of the washing fluid which is carried up by the outer surface of the blanket to the blade 46.

As shown in Figs. 1, 2 and 5, the elongated doctor blade 46 is supported in a manner so that the sharp edge 48 thereof is disposed obliquely across the outer face of the blanket reach 24 and extended at both ends beyond the edges of the blanket, to carry off to a blanket edge, by a sheering action, any lint and ink particles which may remain within the printing area of the outer blanket surface. This oblique arrangement also assures that the blanket joint, if there be one, which is usually disposed straight across the blanket face, will pass under the blade edge without tendency of the latter to catch therein and cause tearing or damage.

It will be understood that with water-soluble inks or color pastes, which may comprise colors and starch, the washing fluid may consist of warm water at a temperature of about 120° F., but if the inks are of the water-insoluble type other suitable washing fluids or solvents, such as a sulphonated oil, may be employed.

In the practice of the invention, the work-piece 17 is fed from the supply roll 16 to between the constantly rotating press cylinder 12 and the gravure roll 13 with the constantly moving backing blanket 10 being interposed between the work-piece 17 and the press cylinder 12 as shown in Fig. 1. The work-piece 17 after passing the gravure roll 13 is separated from the blanket 10 and preferably led upwardly to drying apparatus, not shown.

As shown in Fig. 4 the effective ink-applying length of gravure roll 13 is substantially less than the width of the blanket 10 so as to define flanking zones or margins 49, 49 of the outer blanket surface to which ink will not be applied, as is clearly indicated in Fig. 5. With blankets which may vary in width from forty to fifty inches such ink-free margins 49, 49 will each preferably be about one inch wide. Thus the gravure roll 13 defines the printing path or area 50 indicated in Fig. 5. The effective ink-applying width or length of gravure roll 13 preferably is determined by a relatively narrow felt band or lapping 51 on the press cylinder 12 which is narrower than blanket 10 to permit edges of the latter to bow inward toward the press cylinder surface as shown in

Fig. 4, but, if desired may be determined by the overall length of the roll 13 alone.

In order to assure that the printed patterns or designs are carried out to the selvages of the work-piece 17 the latter is of a width less than the width of the printing area 50. This will define inner zones 52, 52 to which inks or colors will be directly applied by portions of the gravure roll 13 at the ends of its effective ink-applying length. Some of the inks or colors applied to the work-piece 17 also will penetrate through the latter to be deposited upon the blanket outer surface within the printing area 50. It is necessary that these depositions of inks or colors be scrubbed and washed from the blanket outer surface to avoid smearing and blotching of the work-piece. Also, lint particles from the work-piece 17 should be removed from the blanket outer surface before the blanket is returned to the press cylinder 12 so as to avoid printing difficulties.

To clean the blanket 10 it is passed through the scrubbing and washing means where washing fluid is sprayed upon the printing area 50 by spraying nozzle 133 without wetting the flanking margins 49, 49. The wetted printing area 50 of the blanket is then scrubbed by the brush roll 27 which loosens the depositions of inks or colors and removes a large amount thereof also without wetting at least the outer portions of flanking margins 49, 49. Thus the effective scrubbing surface of brush roll 27 must be of a width appreciably less than that of the blanket 10. At least some of the lint and ink particles which pass the scrubbing roll 27 are then washed free from the printing area 50 by the spraying nozzle 33, again without wetting the flanking margins 49, 49.

The upward passage of the reach 24 of blanket 10 will minimize the amount of washing fluid carried in the printing area past the spraying device 33 since some of it will fall or flow back toward and into the trough 29. The washing fluid carried along by the blanket surface, diagrammatically indicated by substantially parallel lines at 53 in Figs. 5, 6 and 9, which remains in the printing area 50 will be carried up to the doctor blade 46 where almost all of it is plowed from the blanket outer surface by the relatively sharp blade edge 48 to fall or flow back along the blanket surface, as indicated at 54 in Figs. 6, 7 and 9, into or toward the trough 29. It has been found in practice that this plowing action is a very distinctive operation and that the fluid does not work along the edge of the blade in contact with the blanket surface to wet the dry margins 49, 49 of the latter. The sharp corner edge 48 of the blade 46 is desirably provided by forming the edge face substantially (but not necessarily precisely) at right angles to the outer surface 55 of the blade, thereby spacing the other corner edge 56 from the blanket outer surface. This is an important feature as will be seen from Figs. 5 and 9 where it is indicated at 57 that small amounts of washing fluid and perhaps some ink mixed therewith creeps up to the outer surface 55 of blade 46 and then flows therealong, as in path 58, to drip off the end at 59. This is the observed operation.

The doctor blade 46 desirably does not remove entirely all of the washing fluid from the moisture-impervious blanket outer surface but permits a very small amount thereof, such as a fraction of a percent, to remain in the printing area

for promotion of the printing operation. This slight amount of moisture in the printing area is of importance since it helps to hold the work-piece 17 in position during the printing operation and permits effective penetration of the fabric with the inks or colors. However, the percentage of retained moisture must not be so great as to cause the inks or colors to run when the work-piece is printed therewith. This rather critical functioning of the doctor blade is assured either by lateral adjustment of the tensioning roll 25, when properly mounted for lateral movement and with the employment of a relatively fixed doctor blade but, preferably, is obtained by rotational adjustment of the doctor blade by means of the hand wheel 45.

Undue wear of the outer surface of the blanket in the printing area 50 by the relatively sharp edge 48 of the doctor blade pressed thereagainst is avoided by lubrication inherently afforded by the washing fluid. It has been found in practice that the doctor blade eventually does produce some noticeable wear in the dry margins 49, 49 while causing relatively little if any apparent wear in the printing area even after the so-equipped printing machine has been used to produce millions of yards of printed fabrics. Of course it is apparent that the wear in the dry margins is of no importance since these zones of the outer surface of the blanket have no function in the printing operation.

Such lint and ink or color particles, graphically indicated in Fig. 5 at 60, as may remain in the printing area after the blanket has passed the spraying device 33 will be collected ahead of the edge 48 of the doctor blade as indicated at 61 and almost all of it, except possibly some amount of color which becomes dissolved in the washing fluid, will be sheered obliquely along in the direction of the arrows to the edge of the blanket at 62 there to fall away from the latter as indicated in an exaggerated manner in Fig. 5 for clarity. This action has also been observed.

It will thus be seen that the depositions of inks or colors to the outer surface of the blanket are limited to a printing area flanked by marginal zones which remain free from such depositions and that the washing and scrubbing are accomplished in a manner so that approximately only the printing area is wetted with a maintenance of the dry flanking margins at the blanket edges to prevent creeping of washing fluid to the inside surface of the blanket thereby avoiding any difficulties which would be attendant upon such condition. Such difficulties would include transfer of moisture from the wet back of the blanket to the felt lapping 51 soon causing the latter to be compacted and hard necessitating its removal and replacement. That felt lapping is very expensive. Removal and replacement of the lapping necessitates complete dismantling of the printing machine. Dismantling and rebuilding of the printing machine and replacement of the lapping may require about six printing hours. Thus it is seen that wetting of or creepage of moisture to the back of the blanket may be a very serious matter and it is thus extremely important that the blanket be returned to the press cylinder with the back of the former dry. The dry surfaces of the blanket at its edges resist wetting by any tendency of the washing fluid to run laterally and longitudinal motion of the blanket and the upward positioning of parts thereof in the washing and fluid-removing means further assure the dryness of the margins.

Further it will be noted that almost all of such washing fluid as remains within the printing area is removed by a definite plowing action which avoids wetting of the clean dry margins while assuring retention of a very small amount of moisture for promotion of the printing operation. Any lint and ink particles which remain in the printing area after passing beyond the spraying device 33 are effectively removed by a definite sheering action obliquely across the blanket surface to an edge thereof where they fall away therefrom.

The simple apparatus described above while permitting effective elimination of a back grey for many operations where its employment is not desired does not prevent its use if it should be desired for certain operations. The apparatus does not interfere in any way with the feed of a back grey between the work-piece 17 and the backing blanket 10 as contrasted with other machines equipped with washing and drying apparatus which have been developed and which, due to their characteristic constructions, prevent the ready employment of a back grey.

Practically all textile printing plants at the present time employ back greys indicating that prior art proposals with regard to blanket washing and drying apparatus have not been entirely satisfactory. This practice is quite generally followed despite the fact that the employment of back greys costs a printing plant thousands of dollars monthly and that the cost of handling and rewashing them is also very large. An apparatus of the present invention equipped as described above has been found to be readily and efficiently operable at a printing speed upwards of one hundred yards per minute which, in this art, is an unusually fast speed and it is to be understood that the cleaning and washing fluid-removing means of the present invention places no practical limitations on the speed at which the machine may operate. One apparatus of the present invention has produced more than two million yards of printed textiles and to all appearances the backing blanket thereof is in as good or better condition than when this machine was first adapted to the present invention, although that backing blanket was not new at the time the machine was provided with the cleaning and drying means of the present invention. As contrasted therewith, in our experience machines equipped with heating driers generally limit the life of a blanket to about one million yards. This particular machine of the present invention has brought about a net saving of at least \$5,000 in back greys alone, but this saving in back greys may be considered to be merely incidental. Better workmanship and production of a superior product, the great increase in output, and saving in amounts of inks or color pastes and ingredients thereof used are also vital factors of the economy effected.

It is to be understood that the term "method of printing" as employed herein is to be broadly construed as encompassing if necessary the operational steps of and complete functioning of machines for applying various types of fluids or pastes to textiles and the like in patterns or designs to give discernible contrasting effects either with respect to contrasting colors, or as to visual contrasts in physical characteristics, such as the application of color pastes or mercerizing fluids and the like, inclusive of interdependent procedural steps attendant upon a continuous modus operandi; and that the term

"printing ink" is to be broadly construed as including within its scope all such pastes or fluids or similar materials employed to effect such results which are capable of being dissolved or removed from parts of such machines, such as backing blankets thereof, by suitable cleansing or washing fluids or solvents. The term "substantially directly back" is employed herein in connection with the return of the backing blanket from the washing means and/or washing fluid-stripping means, e. g., the washing sprays, scrubbing brush and doctor blade, to the press cylinder or printing station. The apparatus and method of the present invention are thus distinguishable from those wherein the backing blanket on its return travel back to the press cylinder is moved over heated drying cans, through hot drying chambers or past other moisture-removing means which employ such amounts of heat to effect removal of washing fluid in the vapor phase as to raise the temperature of the backing blanket or surfaces thereof to a destructive degree. Obviously that term is not used in the sense that the backing blanket is returned from the washing and/or washing fluid-removal means directly back to the press cylinder along a straight-line path as is clear from the disclosure wherein, as indicated in Fig. 1 for example, the backing blanket after it leaves the fluid-stripping means, or doctor blade 24, may be trained over, about or back and forth between deviating means, such as take-up or tensioning rolls or idle rollers, e. g., rolls 25 and 26. Removal of the major portion of the washing fluid, hot or cold, from the washed area of the outer surface of the backing blanket is effected "in liquid state," i. e., washing fluid is stripped from the blanket as a flowing liquid, as distinguished from removal of washing fluid in vapor phase by converting the liquid to vapor with blanket-damaging heat by means of excessively hot drying cans or chambers, and the like.

It will thus be seen that the objects set forth above, among others which will be apparent to those skilled in the art, are efficiently attained by the present invention and, since certain changes in carrying out the above process and in the construction set forth, which embody the invention, may be made without departing from its scope, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described our invention, what we claim as new and desire to secure by Letters Patent is:

1. A continuous method of printing textiles and the like comprising feeding printing ink to printing means having a maximum effective ink-applying width to define the width of a printing area, passing over a rotating press cylinder a loop of an elongated endless backing blanket having a substantially moisture-impervious outer surface which is wider than the maximum effective ink-applying width of said means, printing an elongated strip of material by feeding it between said printing means and said loop of said backing blanket and thereby defining a printing area in an inner zone of the outer surface of said blanket and substantially ink-free flanking mar-

gins, separating the printed strip of material from said blanket and guiding the latter to and through washing means, washing with washing fluid the ink-smeared printing area of the outer surface of said blanket as the latter moves along while restricting the wetting of the outer surface of said blanket substantially to the inner zone inclusive of the printing area thereby retaining substantially dry margins flanking the washed area, removing almost all of the washing fluid from the washed area of said blanket without wetting at least the outer portions of the dry margins thereof, and moving the moisture-surfaced blanket substantially directly back to said press cylinder with a retention of a very small amount of moisture in the wetted area for promotion of the printing operation.

2. A continuous method of printing textiles and the like comprising feeding printing ink to printing means having a maximum effective ink-applying width to define the width of a printing area, passing over a rotating press cylinder a loop of an elongated endless backing blanket having a substantially moisture-impervious outer surface which is wider than the maximum effective ink-applying width of said means, printing an elongated strip of material by feeding it between said printing means and said loop of said backing blanket and thereby defining a printing area in an inner zone of the outer surface of said blanket and substantially ink-free flanking margins, separating the printed strip of material from said blanket and guiding the latter to and through washing and scrubbing means, washing with washing fluid and scrubbing the ink-smeared printing area of the outer surface of said blanket as the latter moves along while restricting the wetting of the outer surface of said blanket substantially to the inner zone inclusive of the printing area thereby retaining substantially dry margins flanking the washed area, removing almost all of the washing fluid from the washed area of said blanket without wetting at least the outer portions of the dry margins thereof, and moving the moisture-surfaced blanket substantially directly back to said press cylinder with a retention of a very small amount of moisture in the wetted area for promotion of the printing operation.

3. A continuous method of printing textiles and the like comprising feeding printing ink to printing means having a maximum effective ink-applying width to define the width of a printing area, passing over a rotating press cylinder a loop of an elongated endless backing blanket having a substantially moisture-impervious outer surface which is wider than the maximum effective ink-applying width of said means, printing an elongated strip of material by feeding it between said printing means and said loop of said backing blanket and thereby defining a printing area in an inner zone of the outer surface of said blanket and substantially ink-free flanking margins, separating the printed strip of material from said blanket and guiding the latter to and through washing means, washing with washing fluid the ink-smeared area of the outer surface of said blanket as the latter moves along while restricting the wetting of the outer surface of said blanket substantially to the inner zone inclusive of the printing area thereby retaining substantially dry margins flanking the washed area, moving said washed blanket from said washing means to means for removing washing fluid, removing by said last-named means almost all of

the washing fluid in liquid state from the washed area of said blanket without wetting at least the outer portions of the dry margins thereof, and then moving the moisture-surfaced blanket substantially at room temperature back to said press cylinder from said washing fluid-removal means with a retention of a very small amount of moisture in the wetted area for promotion of the printing operation.

4. A continuous method of printing textiles and the like comprising feeding printing ink to printing means having a maximum effective ink-applying width to define the width of a printing area, passing over a rotating press cylinder a loop of an elongated endless backing blanket having a substantially moisture-impervious outer surface which is wider than the maximum effective ink-applying width of said means, printing an elongated strip of material by feeding it between said printing means and said loop of said backing blanket and thereby defining a printing area in an inner zone of the outer surface of said blanket and substantially ink-free flanking margins, separating the printed strip of material from said blanket and guiding the latter to and through washing means, washing with washing fluid the ink-smeared area of the outer surface of said blanket as the latter moves along while restricting the wetting of the outer surface of said blanket substantially to the inner zone inclusive of the printing area thereby retaining substantially dry margins flanking the washed area, moving said washed blanket upwardly away from said washing means to and past a doctor blade, pressing said doctor blade against the washed outer surface of said blanket as the latter moves therepast, removing by said blade with a plowing action almost all of the washing fluid from the washed area of said blanket without wetting at least the outer portions of the dry margins thereof and causing the removed washing fluid to flow back with respect to the direction of motion of said blanket, and then moving said blanket substantially at room temperature back to said press cylinder from said blade with a retention of a very small amount of moisture in the wetted area for promotion of the printing operation.

5. A continuous method of printing textiles and the like comprising feeding printing ink to printing means having a maximum effective ink-applying width to define the width of a printing area, passing over a rotating press cylinder a loop of an elongated endless backing blanket having a substantially moisture-impervious outer surface which is wider than the maximum effective ink-applying width of said means, printing an elongated strip of material by feeding it between said printing means and said loop of said backing blanket and thereby defining a printing area in an inner zone of the outer surface of said blanket and substantially ink-free flanking margins, separating the printed strip of material from said blanket and guiding the latter to and through washing means, washing with washing fluid the ink-smeared area of the outer surface of said blanket as the latter moves along while restricting the wetting of the outer surface of said blanket substantially to the inner zone inclusive of the printing area thereby retaining substantially dry margins flanking the washed area, moving said washed blanket upwardly away from said washing means to and past a doctor blade, pressing said doctor blade against the washed outer surface of said blanket as the latter moves therepast with the edge portion of said blade being

5

disposed obliquely across the outer surface of said blanket, removing by said blade with a plowing action almost all of the washing fluid from the washed area of said blanket without wetting at least the outer portions of the dry margins thereof and causing the removed washing fluid to flow back with respect to the direction of motion of said blanket, causing by the oblique arrangement of said blade and the upward travel of said blanket therepast a sheering off of lint and ink particles to an edge of said blanket, and then moving said blanket substantially at room temperature back to said press cylinder from said blade with a retention of a very small amount of moisture in the wetted area for promotion of the printing operation.

6. Apparatus for continuous printing of textiles and the like comprising, in combination, a rotary press cylinder, an elongated endless backing blanket having a substantially moisture-impervious outer surface with a loop thereof passed around said cylinder, printing ink-applying means of an effective width appreciably less than the width of said blanket to define the width of a printing area flanked by margins of appreciable width, washing means receiving said blanket from said cylinder of a length substantially less than the width of said blanket to treat with washing fluid the printing area having dry flanking margins, washing fluid-stripping means beyond said washing means to remove almost all of the washing fluid in liquid state from the washed area of said blanket with removal of lint and ink particles that may remain after washing while retaining dry blanket margins to assure prevention of creepage of moisture to the back surface of said blanket, and means to pass said dry-back blanket from said washing and washing fluid-stripping means substantially directly back to said cylinder.

7. Apparatus for continuous printing of textiles and the like comprising, in combination a rotary press cylinder, an elongated endless backing blanket having a substantially moisture-impervious outer surface with a loop thereof passed around said cylinder, printing ink-applying means of an effective width appreciably less than the width of said blanket to define the width of a printing area flanked by margins of appreciable width, washing and scrubbing means receiving said blanket from said cylinder including brush means of a length substantially less than the width of said blanket and means to supply washing fluid to the printing area while avoiding wetting the flanking margins, means to pass said blanket upwardly from said washing and scrubbing means and substantially directly back to said cylinder, and a relatively thin elongated doctor blade extending at each end beyond the edges of said blanket and having its edge face disposed substantially at right angles to the extended outer surface of its edge portion to provide an inner relatively sharp edge pressing against the outer surface of said blanket with at least the edge portion of said blade lying substantially in a plane which makes an acute angle with the blanket surface on the leading side of said relatively sharp edge and with the latter disposed obliquely across the outer face of said blanket.

8. Apparatus for continuous printing of textiles and the like comprising, in combination a rotary press cylinder, an elongated endless backing blanket having a substantially moisture-impervious outer surface with a loop thereof passed around said cylinder, printing ink-applying means of an effective width appreciably less than the

75

13

width of said blanket to define the width of a printing area flanked by margins of appreciable width, washing and scrubbing means receiving said blanket from said cylinder of a length substantially less than the width of said blanket to treat with washing fluid the printing area while avoiding wetting the flanking margins, an elongated doctor blade extending at each end beyond the edges of said blanket and having a relatively sharp edge pressing against the outer surface of said blanket with at least the edge portion of said blade lying substantially in a plane which makes an acute angle with the blanket surface on the leading side of said relatively sharp edge, means supporting said blade for adjustable rotation about a longitudinal axis for varying the angular relationship between said blade and the outer surface of said blanket and the pressure of the former on the latter, and means to pass said blanket from said washing and scrubbing means substantially directly back to said cylinder past and in surface contact with said blade without subjecting the blanket to action of any other blanket surface-treating means.

9. Apparatus for continuous printing of textiles and the like comprising, in combination a rotary press cylinder, an elongated endless backing blanket having a substantially moisture-impermeous outer surface with a loop thereof passed around said cylinder, printing ink-applying means of an effective width appreciably less than the width of said blanket to define the width of a printing area flanked by margins of appreciable width, washing and scrubbing means receiving said blanket from said cylinder including brush means of a length substantially less than the width of said blanket and means to supply washing fluid to the printing area while avoiding wetting the flanking margins, means to pass said blanket from said washing and scrubbing means substantially directly back to said cylinder, and an elongated doctor blade extending at each end beyond the edges of said blanket and having a relatively sharp edge pressing against the outer surface of said blanket with at least the edge portion of said blade lying substantially in a plane which makes an acute angle with the blanket surface on the leading side of said edge and with the latter disposed obliquely across the outer face of said blanket, and means supporting said blade for adjustable rotation about a longitudinal axis for varying the angular relationship between said blade and the outer surface of said blanket.

10. Apparatus for continuous printing of textiles and the like comprising, in combination a rotary press cylinder, an elongated endless backing blanket having a substantially moisture-impermeous outer surface with a loop thereof passed around said cylinder, printing ink-applying means of an effective width appreciably less than the width of said blanket to define the width of a printing area flanked by margins of appreciable width, washing and scrubbing means receiving said blanket from said cylinder including brush means of a length substantially less than the width of said blanket and means to supply washing fluid to the printing area while avoiding wetting the flanking margins, means to pass said blanket from said washing and scrubbing means substantially directly back to said cylinder, an elongated doctor blade extending at each end beyond the edges of said blanket and having a relatively sharp edge pressing against the outer surface of said blanket with at least the edge portion of said blade lying substantially in a

plane which makes an acute angle with the blanket surface on the leading side of said relatively sharp edge, means supporting said blade for rotation about a longitudinal axis, gear means fixed to said blade, and manual control means for operating said gear means for varying the angular relationship between said blade and the outer surface of said blanket.

11. Apparatus for continuous printing of textiles and the like comprising, in combination a rotary press cylinder, an elongated endless backing blanket having a substantially moisture-impermeous outer surface with a loop thereof passed around said cylinder, printing ink-applying means of an effective width appreciably less than the width of said blanket to define the width of a printing area flanked by margins of appreciable width, washing and scrubbing means receiving said blanket from said cylinder including brush means of a length substantially less than the width of said blanket and means to supply washing fluid to the printing area while avoiding wetting the flanking margins, said washing fluid supply means comprising a nozzle structure adapted to direct jets of washing fluid only against the printing area floatingly supported for movement transversely of the path of said blanket and guide means adapted to receive the running edges of said blanket and connected to said nozzle structure whereby the latter will be moved laterally with any weaving movement of said blanket, means to pass said blanket from said washing and scrubbing means substantially directly back to said cylinder, and means located between said cylinder and said washing and scrubbing means contacting the outer surface of said blanket to remove any remaining lint and ink particles and almost all of the washing fluid with a retention of a very small amount of moisture in the printing area for promotion of the printing operation.

12. Apparatus for continuous printing of textiles and the like comprising, in combination, a rotary press cylinder, an elongated endless backing blanket having a substantially moisture-impermeous outer surface with a loop thereof passed around said cylinder, printing ink-applying means of an effective width appreciably less than the width of said blanket to define the width of a printing area flanked by margins of appreciable width, washing and scrubbing means receiving said blanket from said cylinder including a scrubbing roll of a length sufficient to scrub the ink-smeared printing area of the outer surface of said blanket but less than the width of the latter, and a washing fluid spraying device adapted to spray the printing area of said blanket without spraying the flanking margins of said blanket, said spraying device comprising a nozzle structure adapted to direct jets of washing fluid only against the printing area floatingly supported for movement transversely of the path of said blanket and guide means adapted to receive the running edges of said blanket and connected to said nozzle structure whereby the latter will be moved laterally with any weaving movement of said blanket, means to pass said blanket from said washing and scrubbing means substantially directly back to said cylinder, and a doctor blade located between said cylinder and said washing and scrubbing means pressing against the outer surface of said blanket to remove any remaining lint and ink particles and almost all of the washing fluid with a retention of a very small amount of moisture in the printing area for promotion of the printing operation.

15

13. In an apparatus for continuous printing of textiles and the like with the employment of an elongated endless backing blanket having a substantially moisture-impervious outer surface which is greater in width than the effective width of printing ink-applying means, washing and drying means comprising means to wash the area of the surface of said blanket defined by the ink-applying means without wetting flanking margins, blanket guiding means to provide a run thereof extending upwardly away from said washing means, and an elongated doctor blade to be held in contact with the outer surface of the upward run of the blanket, the edge portion of said blade extending at both ends beyond the edges of the blanket and lying substantially in a plane which will make an acute angle with the outer surface of the blanket on the leading side of the blade to remove with a plowing action almost all of the washing fluid in a liquid state from the washed area with a retention on the washed area of a thin film of liquid to be carried therewith to the ink-applying means to promote the printing operation, the edge portion of said blade being disposed obliquely across the outer surface of the blanket to carry off by sheering action lint and ink particles to an edge of the blanket, the edge portion terminating in an edge face disposed substantially at right angles to the extended outer surface of the edge portion to provide an inner relatively sharp edge for contact with the blanket surface with that construction serving to avoid wetting the flanking margins.

14. In an apparatus for continuous printing of textiles and the like with the employment of an elongated endless backing blanket having a substantially moisture-impervious outer surface which is greater in width than the effective width of printing ink-applying means, washing and drying means comprising means to wash the area of the surface of said blanket defined by the ink-applying means without wetting flanking margins, blanket guiding means to provide a run thereof extending obliquely upwardly away from said washing means, and a swiveled doctor blade overhung by the oblique upward run of the blanket, the edge portion of said blade extending at both ends beyond the edges of the blanket and lying substantially in a plane which will make an acute angle with the outer surface of the blanket on the leading side of the blade to remove with a plowing action almost all of the washing fluid in a liquid state from the washed area with a retention on the washed area of a thin film of liquid to be carried therewith to the ink-applying means to promote the printing operation, the edge portion of said blade being disposed obliquely across the outer surface of the blanket to carry off by sheering action lint and ink particles to an edge of the blanket, the edge portion terminating in an edge face disposed substantially at right angles to the extended outer surface of the edge portion to provide an inner relatively sharp edge for contact with the blanket surface with that construction serving to avoid wetting the flanking margins.

15. The method of printing a textile fabric and the like comprising the steps of passing an elongated strip of such fabric progressively at a printing station between a rotating press cylinder and printing means having a maximum effective

16

printing fluid-applying width to define the width of a printing area, backing the moving textile fabric at the printing station with a substantially moisture-impervious outer surface of an endless dry-back blanket wider from edge to edge than the maximum effective width of the printing means to receive excess printing fluid, the backing blanket being looped about the press cylinder and moving with it and the fabric, printing the moving elongated strip of the fabric at the printing station by such passage with a feed of printing fluid to the printing means thereby defining on the outer surface of the blanket a printing area in an inner zone thereof and flanking margins at the blanket edges substantially free of printing fluid, progressively separating the printed strip of fabric from the blanket beyond the printing station leaving the printing area of the outer surface of a run thereof smeared with printing fluid and the flanking margins substantially clean and dry, progressively moving the smeared blanket run to a washing station remote from the printing station and there washing the printing fluid from the smeared printing area with a cleaning liquid as the blanket moves along while restricting the wetting of the blanket outer surface being washed substantially to the inner zone inclusive of the printing area thereby retaining substantially dry margins flanking the washed area, progressively advancing the washed blanket from the washing station to liquid-stripping means and there removing from the washed area of the moving blanket at least the major quantity of the cleaning liquid in liquid state without wetting at least the outside edge portions of the dry margins of the outer surface of said blanket while maintaining its back surface in substantially dry condition, and thereafter returning the cleaned and stripped dry-back blanket progressively back to the printing station to provide the so-processed outer surface thereof for backing textile fabric to be thereafter printed.

16. Apparatus for continuous printing of textiles and the like comprising, in combination, a rotary press cylinder, an elongated endless backing blanket having a substantially moisture-impervious outer surface with a loop thereof passed around said cylinder, printing ink-applying means of an effective width appreciably less than the width of said blanket to define the width of a printing area flanked by margins of appreciable width, washing and scrubbing means receiving said blanket from said cylinder and including washing fluid-applying means and brush means respectively of a length substantially less than the width of said blanket to wash and scrub the printing area with washing fluid leaving dry flanking margins of the blanket outer surface, washing fluid-stripping means beyond said washing and scrubbing means to remove almost all of the washing fluid in liquid state from the washed and scrubbed area of said blanket with removal of lint and ink particles that may remain after washing while retaining dry blanket margins to assure prevention of creepage of moisture to the back surface of said blanket, and means to pass said dry-back blanket from said washing fluid-stripping means substantially directly back to said cylinder.
